RUDDER MOUNT ASSEMBLY

Otto Brown, Stavanger, Norway

Application July 23, 1957, Serial No. 673,618

Claims priority, application Norway August 4, 1956

2 Claims. (Cl. 114—165)

The present invention relates broadly to a mounting assembly for a pivotally supported member, and more particularly to an improved means for detachably mounting a rudder to the stern post of a boat.

Rudders for boats or skiffs, and particularly life boat rudders, are customarily detached when the boat is stowed or out of water. In conventional practice, the rudder on such small craft is attached to the stern post of the boat by means of eye bolts or the like. Such constructions are satisfactory under some conditions but it has been found practically impossible to install heavy rudders in heavy seas, and the rudder may become disengaged or lost when the boat is launched. Particularly with reference to life boats, it is important that suitable means be used to permit the rudder to be quickly and positively attached to the boat, even though the boat is to be launched in an emergency and in rough seas.

An object of the present invention is to provide a mounting assembly for rudders of this type providing for quick detachment, and positive quick attachment of the rudder to the stern post of a life boat.

Another object of the present invention is to provide mounting means for rudders whereby the rudder is very easily put in place and removed, and which is securely locked into position when mounted.

A further object of the present invention is to provide an improved construction for attaching a rudder to a small boat which permits the boat to be launched in heavy seas without danger that the rudder may become disengaged or lost.

A still further object of the present invention is to provide a construction whereby a rudder may be selectively engaged with and disengaged from a boat, without removal or disconnection of the mounting means from the boat.

An additional object of the present invention is to provide mounting means for boat rudders incorporating therein, as an integral portion, a tiller construction which also comprises a portion of the rudder mounting mechanism.

A still further object of the present invention is to provide a rudder mounting device which is simple and sturdy in construction, and which is easily attachable to stern posts of boats and the like.

Other and further objects and advantages of the invention will become apparent from the following detailed description of embodiments thereof when taken together with the accompanying drawings in which:

Fig. 1 is a fragmentary side elevational view of the rudder mounting means of the present invention;

Fig. 2 is a sectional view taken on line 2—2 of Fig. 1;

Fig. 3 is an enlarged fragmentary view, partly in section, showing a detail of the construction;

Fig. 4 is an enlarged fragmentary view, partly in section, of a modified form of a detail of construction;

Fig. 5 is a perspective view of the rudder post of pintle for mounting on the stern post of a boat;

2

Fig. 6 is a perspective view of a rudder mounting tube for coacting with the post of Fig. 5;

Fig. 7 is a perspective view of an extension member for the rudder post and constituting a tiller; and

Fig. 8 is a perspective view of a handle for the rudder assembly.

The invention comprises essentially the provision of a fixed rudder post or pintle adapted for rigid securement to the stern post of a boat, and a rudder supporting tube 10 rotatably mounted on the rudder post having the rudder attached thereto. Additionally, an extension of the rudder post is provided which is rotatably mounted on the top end of the post and this extension includes a knee-joint or pivotal mounting whereby a portion can be selectively placed in horizontal or vertical position to facilitate mounting of the rudder tube and rudder on the rudder post. Further the invention includes a tiller handle which is quickly and easily attached to or detached from the rudder post extension which additionally constitutes a tiller for the rudder.

Referring now more particularly to the drawings, a portion of a boat, such as a life boat, is shown at 16, having a stern post 12 in the usual manner. A rudder post or pintle 14 is secured to the stern post 12 by means 25 of a lower bracket 16 fastened to the stern post by screws or bolts 18, and an upper bracket 20 attached to the stern post by screws or bolts 22. These brackets 16 and 20 preferably are attached to the rudder post 14 by welding or the like. For reasons appearing hereinafter, 30 the front or nose portion of upper bracket 20 is narrowed at 24. The weld is indicated at 26. As shown in Figs. 3 and 5 of the drawings, the upper end of rudder post 14 is provided with screw threads 28 and an undercut or non-threaded portion at 30.

35 A rudder post extension, generally designated 32, consists of an elongated rod 34 of substantially the same diameter as rudder post 14. At one end of the rod 34 there is a rotary sleeve 36 pivotally mounted at 38, and which is provided with an internally threaded cup 40, 40 adapted for screw threaded coaction and connection with the screw threaded portion 28 of rudder post 14. This post extension, by means of interengagement of the threads in cup 40 with the threaded portion 28, and in conjunction with the pivoted mounting of the rod 34 45 constitutes a rudder post extension, the details of which are shown in assembled relationship in Fig. 3. It will be noted, due to this construction, that the elongated rod 34 can be raised to a vertical position in alignment with rudder post 14 or placed in a horizontal position where- 50 in the post extension serves in part as a tiller. Additionally, the rotary sleeve 36 can be rotated with respect to the axis of rudder post 14 and the amount of rotation permissible, in the embodiment of Fig. 3, is governed by the relative positions of the threaded portions 28 55 and the threads in threaded cup 40. Spacings are indicated at 42 at the upper end of the post and at 44 at the lower end of threaded cup 40, in conjunction with the undercut or non-threaded portion 30 of rudder post 14. Additional suitable rotation limiting means can be 60 incorporated if desired.

A modification of the connection between the rudder post and post extension is shown in Fig. 4 wherein the rudder post 46 has an upper end 48 of lesser diameter, and a smooth peripheral surface thereon. A cup 50 member having an internal bore 52 at its outer end is pivotally mounted on a rod similar to that shown at 34 in Figs. 3 and 7. This cup is in slidable and rotary engagement with upper end 48 of the post 46 as shown in Fig. 4. A peripherally extending slot 54 is provided through the wall of the member 50 and extends into the bore 52. A set screw 56 is threadedly engaged in an opening formed in the upper end 48 of rudder post 46,

and the outer end thereof extends into the slot 54. By means of this construction, the rotational movement of the extension or cup 50, with respect to the axis of rudder post 46, is determined and limited in a manner similar to that of the construction shown in Fig. 3.

The foregoing structure constitutes that portion of the assembly adapted for securement to the boat in fixed relationship therewith. The movable portion of the rudder assembly is generally designated 58 and includes a rudder blade 60 of a usual shape and construction, preferably wood. The rudder 60 is fastened to rudder tube 62 which is of tubular configuration, by means of brackets 64 and screws or bolts 66 or the like. The brackets are welded as at 68 to tube 62. It will be seen from Fig. 6 of the drawings that the member 62 includes an elongated open ended tube 70 having a longitudinally extending slot 72 in the bottom portion thereof, widening out at 74 in proximity to the middle of the tube. The upper portion of the tube is unbroken.

The upper bracket 64 has an extension 76 thereon of tubular configuration welded to the bracket at 78 and the free end is provided with a spring clip 80 which opens upwardly. The spring clip is formed of two half portions having complementary semi-cylindrical portions 82, the purpose of which will be shown hereinafter.

The post extension 32 can be placed in a vertical position which can be maintained by the relationship of the free end 84 of rod 34 with respect to the bottom of the slot 86 formed at the upper end of the rotary sleeve 36. When it is desired to mount the rudder assembly portion 58, extension 32 is first swung into horizontal position over the boat, and the end of this rod can be inserted in the tube 70 which can be slid over the rod 34, and subsequently the rod 34 is turned up vertically so that the rudder secured thereto will slide downwardly over and on to the rudder post 14. Due to the provision of the slot 72 and the shape and dimension of the nose portion 24, no interference will be encountered by bracket 20 secured to the rudder post 14. The widened portion 74 of the slot permits rotational movement of the rudder tube with respect to the rudder post. Since the upper portion of the rudder tube is not provided with a slot, it serves as a downward movement abutment for proper positioning of the tube on the rudder post. Following this mounting, the post extension 32 is then lowered to horizontal position and will be firmly gripped in the spring clip 80 by means of the grooves 82 gripping the outer periphery of the elongated rod 34. By proper dimensioning of the length of the rod 34, the post extension 32 also can serve as a tiller for the rudder.

As shown in Fig. 7 of the drawings, a peripheral groove 88 is formed in the rod 34 intermediate its ends. A handle 90 consisting of a hand grip portion 92, preferably of wood, is provided at its inner end with a cylindrical, longitudinally extending recess 94, and formed as an extension thereof is a tube 96 having substantially the same internal diameter as that of cylindrical recess 94 and mounted on the end of the handle 90 by means of collar 98. A spring clip 100 having a hand grip 102 is secured to the external surface of tube 96. After the rudder has been mounted as described hereinbefore, the handle can be slid on to the free end of post extension 32 and the lip 104 of spring clip 100 will engage in the slot 88 to lock the portions in operative relationship. The hand grip 102 can be used for raising the lip 104 from

slot 88 to permit disengagement of the handle 90 from the rod 32.

When in assembled relationship, the movable portion of the rudder assembly, including the rudder tube 62 and rudder blade 60, can be rotated or pivoted with respect to the rudder post and accordingly with respect to the stern post and the boat proper for use as a rudder in a normal manner.

For detaching the movable portion, the reverse of the sequential steps set forth above is followed, and consists in removing handle 90, raising extension rod 32 into vertical position, sliding rudder tube 62 upwardly until free of the knee-joint formed between rudder post 14 and extension rod 32, and thereafter lowering rod 32 to the horizontal position, and sliding the movable portion over the extension rod.

The foregoing description and drawings disclose a construction embodying the main features and characteristics of the present invention and some of the details have been included to describe an operative embodiment. Manifestly, many changes in minor details are possible within the scope of the invention. As an example, the connection of the extension rod with the rudder post can take various forms such as a plug threadedly engaging in mating bores in the contacting ends of the extension and post to which the rod 36 can be engaged. Further, the rudder tube can be replaced by screw eyes or the like and the specific attaching means for the handle could be modified to include a spring clip on the hand grip engaging over the spring clip formed on the upper bracket extension thereby eliminating the peripheral groove.

Such modifications as will appear obvious to those skilled in the art are intended to be included within the scope of the present invention and limited solely by the appended claims.

I claim:

1. In combination a fixed rudder post adapted for securing to the stern post of a boat, a rudder support rotatably mounted on said rudder post, an extension having a knee-joint therein rotatably mounted on the upper end of said rudder post whereby said extension can be aligned with or angularly disposed to said stern post to permit the rudder support and a rudder secured thereto to be placed on the extension when in horizontal position, and to be slid on to the rudder post, when said extension is in vertical position, in alignment with the stern post, means for selectively interconnecting said rudder support and said extension, said extension constituting a rudder tiller when in horizontal position and fixed to said rudder support.

2. The device of claim 1, said rudder support including brackets, a rudder blade secured in said brackets, an extension on the upper one of said brackets, said interconnecting means including a spring clip on said extension, said extension being engageable in said clip for constituting a tiller for said rudder.
